US00D987891S

(12) **United States Design Patent** (10) **Patent No.:** **US D987,891 S**
Lotti (45) **Date of Patent:** **** May 30, 2023**

(54) **APPLICATOR FOR APPLYING LASH
EXTENSIONS**

(71) Applicant: **Lashify, Inc.**, North Hollywood, CA (US)

(72) Inventor: **Sahara Lotti**, North Hollywood, CA (US)

(73) Assignee: **Lashify, Inc.**, North Hollywood, CA (US)

(**) Term: **15 Years**

(21) Appl. No.: **29/726,244**

(22) Filed: **Mar. 2, 2020**

Related U.S. Application Data

(60) Continuation of application No. 29/723,252, filed on Feb. 5, 2020, which is a division of application No. 29/703,954, filed on Aug. 30, 2019, now Pat. No. Des. 890,430, which is a continuation of application No. 29/692,817, filed on May 29, 2019, which is a division of application No. 29/667,344, filed on Oct. 19, 2018, now Pat. No. Des. 850,715, which is a continuation-in-part of application No. 15/968,453, filed on May 1, 2018, now Pat. No. 10,638,826, application No. 29/726,244 is a continuation-in-part of application No. 15/968,453, filed on May 1, 2018, now Pat. No. 10,638,826, said application No. 29/667,344 is a continuation-in-part of application No. 15/968,361, filed on May 1, 2018, now Pat. No. 10,660,388, application No. 29/726,244 is a continuation of application No. 15/968,361, filed on May 1, 2018, now Pat. No. 10,660,388, said application No. 15/968,453 is a continuation of application No. PCT/US2017/067513, filed on Dec. 20, 2017, said application No. 15/968,361 is a continuation of application No. PCT/US2017/044217, filed on Jul. 27, 2017.

CLAIM

An ornamental design for an applicator for applying artificial lash extensions, as shown and described.

DESCRIPTION

FIG. 1 is a perspective view of an applicator for applying artificial lash extensions;

FIG. 2 is a top side view thereof;

FIG. 3 is a bottom side view thereof;

FIG. 4 is a right side view thereof;

FIG. 5 is a left side view thereof;

FIG. 6 is a front side view thereof; and,

FIG. 7 is a back side view thereof.

The broken lines consisting of evenly spaced dashed lines in the drawings depict parts of the applicator for applying lash extensions that form no part of the claimed design. The broken lines consisting of long and short dashed lines in the drawings depict the boundary of the claimed invention and it is understood that the claim extends to the boundary that forms no part of the claimed design.

1 Claim, 4 Drawing Sheets
